[57] **CLAIM**

The ornamental design for a lighted bookmark, as shown and described.

DESCRIPTION

FIG. 1 is a left side perspective view of a lighted bookmark, with the light-bearing neck retracted into the body, showing my new design;

FIG. 2 is a right side perspective view thereof, with the light-bearing neck in the extended position;

FIG. 3 is a rear side perspective view thereof;

FIG. 4 is a side elevational view thereof, with the light-bearing neck in the retracted position;

FIG. 5 is a rear elevational view thereof, with the light-bearing neck in the retracted position;

FIG. 6 is a top plan view thereof, with the light-bearing neck in the retracted position; and,

FIG. 7 is a bottom plan view thereof, with the light-bearing neck in the retracted position.

FIG. 1

FIG. 2

FIG. 3

FIG. 7
